UNITED STATES PATENT OFFICE.

WILLIAM N. BLACKBURN, OF DREXEL HILL, PENNSYLVANIA.

FLUE-WALL FACING.

Application filed December 28, 1921. Serial No. 525,491.

To all whom it may concern:

Be it known that I, WILLIAM N. BLACKBURN, a citizen of the United States, residing at Drexel Hill, in the county of Delaware and State of Pennsylvania, have invented certain new and useful Improvements in Flue-Wall Facings, of which the following is a specification, reference being had to the accompanying drawings.

10 Heretofore flue walls leading from the fireplace, particularly the sloping or inclined parts thereof are more or less rough, irregular, or caused to be formed with pockets, due to the arrangement of the ends of the 15 brick work forming the chimney. When the flue walls are constructed of concrete or other material, they are more or less irregular or rough, and such construction especially when occurring on sloping or inclined 20 parts of the flue, the smoke or products of combustion from the fireplace are more or less retarded.

It is, therefore, the purpose of the present 25 invention to provide a metallic flue wall lining, especially upon the sloping or inclined portions thereof, to provide smooth surfaces for the smoke or products of combustion, in order to prevent them from being retarded during their passage through the flue.

30 Another purpose is to provide a flue wall facing or lining, which not only insures a smooth surface for the smoke or products of combustion, but also acts to support the material of the wall of the flue or chimney, and 35 in so doing to obviate the rough or irregular surfaces.

Still another purpose is the provision of a flue wall facing or reinforcement in the form of a metallic plate having a marginal reinforcement flange, which acts to strengthen 40 the plate and keep it from warping, and furthermore to assist the plate or flue wall section in supporting the wall of the flue and the material constituting the wall, the marginal reinforcement also acting to reinforce 45 the plate, while in position in the flue.

A still further purpose is the provision of a flue wall facing or lining including lateral lugs or projections embedded in the flue 50 wall, to assist materially in holding the plate or facing in position against the flue wall.

A further purpose embodies a flue wall facing including upwardly projecting lugs for engagement on the interior of the terra 55 cotta flue lining, there being shoulders on the plate adjacent said retaining lugs, upon

which the lower edge of the terra cotta lining engages, thereby supporting the terra cotta flue lining in position.

While the design and construction at 60 present illustrated and set forth are deemed preferable, it is obvious that as a result of a reduction of the invention to a more practical form for commercial purposes, the invention may be susceptible of changes, and 65 the right to these changes is claimed, provided they are comprehended within the scope of what is claimed.

The invention comprises further features and combination of parts, as will be herein- 70 after set forth, shown in the drawings and claimed.

In the drawings:—

Figure 1 is a view in front elevation of a fireplace, showing the base of the chimney 75 broken away, to illustrate the flue walls, particularly the sloping or inclined portions thereof;

Figure 2 is a vertical sectional view on line 2—2 of Figure 1, also showing the arrangement of the flue wall facing or lining;

Figure 3 is a detail perspective view of one of the flue wall linings or facings, illustrating the smooth surface thereof;

Figure 4 is a detail perspective view of 85 said flue wall facing or lining, showing the opposite side thereof, in order to illustrate the marginal reinforcement, the terra cotta supporting lugs, and the lateral lugs for the support of the plate; and

Figure 5 is a detail perspective view of a 90 modified form of flue wall facing or lining, showing the lateral lugs dispensed with.

Referring to the drawings, 1 designates the chimney, 2 the fireplace, and 3 the 95 smoke flue, which leads or extends from the base of the chimney, and which is provided at its lower portion with perpendicular side walls 4, including the inclined or sloping walls 5. These sloping or inclined 100 walls merge into the opposite walls of the perpendicular portion 6 of the flue. In fact the sloping or inclined walls are directly opposite each other, and heretofore their surfaces have been rough, irregular, 105 due to the arrangement of the bricks forming the wall.

In order to avoid the rough irregular surfaces of the inclined or sloping walls of the flue, flue facing plates or linings 7 110 are arranged adjacent the inclined or sloping walls of the flue. These plates may be

constructed of any suitable material, such as cast iron or terra cotta, clay, or any other fire resisting material, preferably terra cotta. The facings or linings are shown as being constructed of metal, and it is obvious that should they be constructed of terra cotta, clay or the like, they will be made thicker, in order to withstand the strain of the wall, as well as the strain 10 of the terra cotta portion of the flue portion 6.

The flue wall facing is provided with a marginal reinforcement 8, and projecting laterally from the opposite longitudinal 15 edges thereof are lugs 9, which extend into the brick work of the chimney, for the purpose of supporting the flue wall facings. The lugs 9 are engaged in the wall, when the chimney is being constructed. While 20 these lugs 9 are shown as being flat and angular in cross section, it is obvious that they may be constructed in any other suitable shape.

Projecting upwardly from the upper part 25 of the flue wall facings are lugs 10, which are arranged at obtuse angles to the plate. These lugs 10 engage on the interior of a terra cotta piping 11, which constitutes the upper part 6 of the flue. The outer face 30 of the plate or flue wall facing immediately adjacent the lugs 10 is provided with lateral projecting lugs 12 causing shoulders 13 to be formed, upon which the lower end of the terra cotta piping 11 engages, 35 thereby not only supporting the terra cotta piping 11, but also the plates act to support the material of the chimney.

The marginal reinforcement 8 is formed on the outer face of the plate or facing, 40 while the inner face is smooth and unobstructed, so as to provide a smooth surface for the smoke or products of combustion in its passage through the flue. The flue facings or linings are disposed a substantial 45 distance above the frame 14 of the damper 15, so as to allow the damper 15 to raise or open its full distance. The damper 15 has a rack 16, which engages the frame 14, so as to hold the damper in 50 different positions. In order to adjust the damper 15 the rack 16 is grasped by the hand of the operator, at the free extremity or end of the rack, and moved in order to disengage any of its teeth with the frame 55 14, so that any other of said teeth may be engaged with the edge of the opening of the frame. By this arrangement and operation the damper 15 may be disposed in different adjusted positions. However 60 some suitable heat resisting material may be used in the hand of the operator to grasp the rack for the purpose of adjusting the damper even though the fireplace contains a fire.

65 In Figure 5 the lateral lugs 9 are dis-

pensed with, otherwise the construction of the flue wall facing is substantially the same.

In either case the flue wall facing or lining acts to support the terra cotta piping or lining of the perpendicular portion of the flue 6, and also the material of the chimney. The chimney may be constructed of any suitable material, such as brick, stone or concrete.

70 It will be noted that the flue wall lining or facing has no flange arranged through the front of the mantle, which reinforces the front and back walls of the chimney.

75 After the fireplace and chimney has been constructed until it reaches an approximate height as indicated at a, Figure 1 the facing plates or linings 7 are disposed in positions so that their lower edges rest upon the brick work. Bolts 20 are then inserted in the 80 openings or apertures 23, there being nuts 21 and 22 threaded upon the rods, adjacent the inner and outer faces of the plates or facings, to support the plates in position and holding them up until the wall 85 is built up over the plates, in order that the lugs 9 may be used to support the plates. Before the wall is completed, the rods 20 may or may not be removed. However the illustrations in Figures 1 and 2 90 show the rods 20 remaining in position, and it may be possible that the rods will tend to reinforce the plates, more so than if the rods were taken out.

95 Furthermore the lateral lugs have ample 100 protection to withstand the entire side wall construction, without interfering with the front wall construction, which is the foundation upon which the present invention is based.

105 The invention having been set forth, what is claimed is:—

1. As an article of manufacture, a flue wall facing, comprising a body to be arranged adjacent a flue wall, the upper part 110 of the facing having projections engaging on the interior of a flue wall piping, to not only support the same, but also acting to hold the facings in place, and means at the bases of said projections, upon which the 115 lower end of the upper part of a flue piping rests, thereby supporting the flue piping and assisting in holding the facing in position.

2. As an article of manufacture, a flue wall facing, comprising a body to be arranged adjacent a flue wall, the upper part 120 of the body having shoulders upon which a flue piping rests, thereby not only supporting the piping but also retaining the facing 125 in position, the upper part of the facing also having projections engaging on the interior of the flue piping.

3. As an article of manufacture, a flue wall facing, comprising a body provided with a marginal reinforcement, said body 130

being disposed in contact with the flue wall, to protect the same, the inner face of the body being smooth, thereby avoiding the retardation of the products of combustion, 5 the upper part of the body having means engageable with the lower edge of a flue piping, to support the piping in the flue, the upper part of the body also having projections engaging within and against the side walls 10 of the flue piping.

4. As an article of manufacture, a flue wall facing, comprising a body provided with lateral lugs, adapted to project into the walls of a chimney, said body having adjoining shoulders for engagement with the lower edge of a flue piping, to support the piping, the upper part of the body also having projections engaging on the interior of the piping. 15

5. As an article of manufacture, a flue wall facing, comprising a body provided with a marginal reinforcement, and having lateral lugs, extending into the wall of the chimney, to support the facing, to support 20 the body, the upper part of the body having

shoulders to be engaged by the lower edge of a flue piping, to not only support the piping but to hold the body in place, the upper part of the body also having projections engaging on the interior of the flue piping. 30

6. As an article of manufacture, a pair of opposite individually supported flue wall facings, each provided with means anchoring in the flue wall for retaining said facing in position, a flue piping in the flue above the 35 facings, and means on the upper parts of the facings to support the flue piping.

7. In a device as indicated, the combination with a flue piping adapted to fit within a chimney, of individual insertable opposite 40 flue wall facings diverging downwardly and laterally from opposite portions of the piping and being anchored in corresponding opposite diverging faces of the chimney, and means carried by the facings and protruding 45 into the piping to support the piping in position.

In testimony whereof I hereunto affix my signature.

WILLIAM N. BLACKBURN.
